8 Claims. (Cl. 333—11)

This invention relates to wave filters for use in waveguides and in particular to band-pass and low-pass filters.

The invention involves the use of a waveguide hybrid junction and utilizes the cut-off principle of wavelength selection and rejection. Filters according to my invention are especially useful at frequencies above 10 kmc./sec.

An object of the invention is to devise a wave filter of the band-pass or low-pass type of relatively simple construction by the use of cut-off sections of waveguide in conjunction with a biconjugate directional coupling device such as a magic-tee, a short-slot hybrid, or similar devices.

Among the possible advantages to be gained from the use of such filter structures are the simplicity of the design procedure and the ease of fabrication in those frequency bands where good hybrid junctions are available. Furthermore, the only important tolerance is on the widths of the cut-off waveguide sections. As these widths are the largest critical parameters of the structure, the actual mechanical tolerances need not be excessively small. Filters of this type also are well suited for use in filter partitioning schemes as the matched loads terminating the cut-off sections can be replaced by a short-slot hybrid or a similar device to recombine signals which would otherwise be absorbed by the loads. The recombined signals may then be fed through successive stages of drop-out filters. Furthermore, the input impedance to a hybrid cut-off filter is fairly well matched to the input line, even in the filter rejection band. Finally, the dependence of the cut-off frequencies on waveguide widths provide a technique for constructing simple variable pass-band filters.

A further object of the invention is to devise a waveguide section having a variable cut-off characteristic whereby the band width of the filter may be varied.

Two forms of the invention are illustrated in the accompanying drawing in which FIG. 1 is a diagrammatic showing of one embodiment involving the use of a short-slot hybrid junction.

FIG. 2 shows a second embodiment using a magic-tee junction.

FIG. 3 illustrates a suitable arrangement for varying the cut-off frequency of a waveguide section forming part of the filter.

FIG. 3a is a sectional view of FIG. 3 along the line 3a—3a; and

FIGS. 4, 5, and 6 show subject matter related to the instant invention.

Referring to FIG. 1, a conventional short-slot hybrid junction is formed by two waveguide sections 10 and 11 coupled together through a short-slot 5 formed in a common wall between the two sections. The four ports of the hybrid junction are designated 1, 2, 3 and 4 respectively.

The input to port 1 is connected through a linear taper section 10a to a waveguide section 10b of length 1' and width a' to provide a cut-off frequency equal to or somewhat below f₁, the lower frequency of the band to be passed. Two conjugate arms of the hybrid terminating in ports 2 and 3 are connected through taper sections 10c and 11c to identical cut-off waveguide sections 10d and 11d which are in turn terminated in matched re-

2

sistive loads represented at R, R. Sections 10d and 11d have the same width a'' to provide a cut-off frequency equal to or somewhat above f₂ at the upper end of the band to be passed. Wave energy within the selected band f₁ to f₂ is taken off from port 4 and applied to a load represented by R_L.

When a signal is applied to the input port 1 of the filter through section 10b, only those frequencies above the cut-off of section 10b will enter the hybrid at port 1. In the ideal case, the power into the hybrid divides equally and appears at ports 2 and 3 with the signals at these ports 90 degrees out of phase. If the signal frequency is below the cut-off of the guide sections 10d and 11d terminating these ports, the signal power undergoes complete reflection. Due to the 90 degrees difference in phase between the two signals reflected from ports 2 and 3, and the additional phase displacement each reflected signal experiences in traversing the coupler, the reflected signals arrive in phase at port 4 and in phase-opposition at port 1. Therefore, input signals having frequencies between the cut-off frequency of the input guide section 10b and the cut-off frequency of the two line sections 10d and 11d connected to ports 2 and 3 will be transmitted to port 4 and will suffer no attenuation in the ideal case. Signals at frequencies above the upper cut-off frequency f₂ will arrive at ports 2 and 3, be transmitted through the two guide sections 10d and 11d and be absorbed by the resistive terminations to these two sections. Thus these signals will not appear at port 4 and the filter has a band-pass characteristic.

FIG. 2 shows a similar filter employing a conventional magic-tee junction in place of the short-slot hybrid. The magic-tee is of conventional construction having an input arm 12, two balancing or conjugate arms 13 and 14, and an output arm 15. The ends of these arms present ports 1, 2, 3 and 4 corresponding to like-numbered ports in FIG. 1. Input energy is applied to port 1 through a cut-off waveguide section 12a connected to port 1 through a uniform taper section 12b, the input end of section 12b being connected through a taper section 12c to a supply section 12d of larger transverse dimensions. As in FIG. 1, the section 12a has the width a' and the proper length to provide cut-off at a frequency equal to or somewhat below f₁, the lowest frequency in the band to be passed. Arm 13 is terminated in a cut-off section 13a connected to port 2 through a taper section 13b, section 13a corresponding to cut-off section 10d in FIG. 1. And likewise, arm 14 is terminated in cut-off section 14a which is connected to the arm through a taper section 14b, and cut-off section 14a corresponding to cut-off section 11d in FIG. 1. Cut-off sections 13a and 14a are identical and provide cut-off at or somewhat above the frequency f₂.

The basic principle of operation of FIGURE 2 differs from the previous case in that there is no phase difference between the signals arriving at the conjugate arms 2 and 3. In order to cause signals reflected from these ports to emerge from port 4, it is necessary to reverse the phase of one of the reflected waves re-entering the tee. This is accomplished by the introduction of a one-quarter wavelength line section between one of the terminals or ports 2 or 3 and the corresponding cut-off terminating section. For example, section 14c may be inserted between port 3 and taper section 14b and will have a length to produce a 90 degree phase shift at the mid-band frequency. This length of line has no effect on the performance of the filter in its rejection band, although the presence of this length of line will affect the performance of cascaded filters of this type.

Low-pass filter operation of FIGURES 1 and 2 can be obtained by omitting the cut-off waveguide section at the input to port 1.

The filter arrangement shown in FIGURES 1 and 2 may be made to cover bands of different widths and for different frequency limits by providing known arrangements for adjusting the cut-off frequencies of the input line sections 10b and 12a, respectively, and for adjusting the cut-off frequency of the sections 10d, 11d, 13a and 14a. One novel arrangement especially useful for this purpose is illustrated in FIGURES 3 and 3a. This arrangement will be described for use at 12a in the input arm 12 of FIGURE 2, but it will be understood that it may be used in the location of any of the other cut-off sections of FIGURES 1 and 2.

As shown in FIGURE 3, the cut-off section 12a is of rectangular form having a width *a* and a height *b*. This section is provided at its ends with oppositely extending tapered sections 12b and 12c for connection in one arm of the hybrid junction, and a slot 16 is formed along the middle of the top wall of all three sections 12a, 12b and 12c. A metallic vane or plate 17 is mounted by structure not shown to move into and out of the slot 16 to produce a ridge effect in the three sections which effects a change in the cut-off frequency of the section 12a. As shown in the drawing, the lower edge of plate 17 has a straight parallel portion 17a extending throughout the length of the cut-off section 12a, and tapered portions 17b and 17c extending over the extent of line sections 12b and 12c, respectively. The tapered portions 17b and 17c prevent undesired reflections from the central portion 17a. Spring fingers 16a and 16b (FIG. 3a) arranged on opposite sides of slot 16 engage opposite faces of plate 17 to insure good contact between the plate and the top wall of the line sections.

The cut-off frequency of the waveguide decreases as the depth to which the ridge is inserted into the waveguide is increased. Therefore a cut-off section is designed to have the cut-off at the highest required frequency when the ridge is completely removed from the guide.

Reference is made to a published description of my invention appearing in the Institute of Radio Engineers Transactions, volume MTT-7, January 1959, pages 163 to 167.

Other forms of the invention include the use of a strip transmission line hybrid ring with cutoff sections of trough waveguide as shown in FIG. 4. Tunable filters can be obtained by using sections of trough waveguide whose cutoff frequency can be varied by adjusting the width of the center fin as shown in FIG. 5. Coaxial line hybrid rings can also be used with either variable trough waveguide cutoff sections or coaxial line cutoff sections of the type shown in FIG. 6. These forms of the invention are particularly useful at the lower microwave frequencies (500-5000 mc./sec.).

The term "hybrid junction" is used herein in a broad sense to apply to any 4-port junction, and is generic with respect to FIGURES 1 and 2.

I claim:

1. A band-pass waveguide filter comprising a hybrid junction having an input port, an output port, and two conjugate ports receiving energy equally from said input port, a cut-off waveguide section connected to supply energy to said input port and having a cut-off frequency at the lower end of the band to be passed, identical cut-off waveguide sections connected to receive energy from said conjugate ports and having a cut-off frequency at the upper end of the band to be passed, matched terminations for said identical cut-off sections for preventing reflection of wave energy above the cut-off frequency of said identical sections, said hybrid junction including means for effecting transmission of wave energy reflected from said identical cut-off sections in like phases to said output port.

2. A filter according to claim 1 wherein said hybrid

junction comprises a pair of parallel waveguide sections having a common wall and being coupled together through a slot formed in said common wall.

3. A filter according to claim 1 wherein said hybrid junction comprises a magic-tee junction.

4. A filter according to claim 1 wherein said cut-off sections embody means to adjust the value of the cut-off frequency.

5. A filter according to claim 1 wherein each cut-off section has a width smaller than the width of the arm of the hybrid junction to which it is connected, each cut-off section being connected to the respective junction arm through a tapered section of the same height as the cut-off section.

15 6. A filter according to claim 1 wherein each cut-off section has a width smaller than the width of the arm of the hybrid junction to which it is connected, each cut-off section being connected to the respective junction arm through a tapered section of the same height as the cut-off section, the top walls of said cut-off and tapered sections having a slot formed along the center thereof, and a metallic plate mounted to move into said slot transversely of said sections, said plate having its entering edge tapered over the portion which enters the 25 slot in said tapered section.

7. In a wave filter, the combination of a main rectangular waveguide section of uniform transverse dimensions throughout its length, a tapered section coupled to the input end of said main section and being of the same height as said main section and of greater width at its 30 input end than said main section, the top walls of said sections having a slot formed along the center thereof, and a metallic plate mounted to move into said slot transversely of said sections, said plate having its entering edge tapered over the portion which enters the slot in said tapered section.

8. In a wave filter, the combination of a main rectangular waveguide section of uniform transverse dimensions throughout its length, an outwardly tapered section coupled to each end of said main section, each tapered section being of the same height as said main section and of greater width at its outer end than said main section, the top wall of said main section having a slot formed along the center thereof and extending into the top wall of each tapered section, and a metallic plate mounted to move into said slot transversely of said sections, said plate having its entering edge tapered over the portions which enter the slot in said tapered sections.
